UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

CUTTER CHAIN.

Application filed March 17, 1923. Serial No. 625,909.

This invention relates to improvements in cutter chains for mining machines, and more particularly to cutter blocks for holding the cutter bits, and has for its principal object 5 to produce a simple and durable construction of cutter blocks of the class described.

My invention may be best understood by reference to the accompanying drawings in which:

Figure 1 is a side view of a cutter chain block embodying my invention.

Figure 2 is an enlarged view in perspective of the reverse side of the cutter chain block shown in Figure 1.

Figure 3 is a sectional view of the chain showing it in position in a cutter head of a mining machine.

Figure 4 is a section taken on line 4—4 of Figure 1.

Figure 5 is a section taken on line 5—5 of Figure 1.

Figure 6 is a side view of a forged or cast blank for the cutter block before machining the bit-receiving recess.

Figure 7 is a view similar to Figure 6, after machining the bit-receiving recess.

The principal function of a cutter chain block is to support the cutter bit securely in position to engage the material to be cut.

The cutter bits project outwardly at various angles to the block, as shown in Figure 3, and are subject to enormous rearward and lateral stresses during the cutting operation, which often causes the bit to work loose in

its securing device even when tightened as much as practicable by the usual methods.

The most satisfactory form of securing device now in general use includes an aperture formed in the top of the block, into which the cutter bit is inserted endwise. The bit

is clamped against the rear wall of the aperture, by various means, such as set screws or their equivalents.

One objectionable feature of the ordinary form of block is that the cutter bits often get wedged in the aperture, making it very difficult to remove them, especially when the outer end is broken off. Furthermore, such blocks are more or less difficult to manufacture in an efficient and economical manner, as for example, when such blocks are formed of castings it is necessary either to core an aperture for the cutter bit or machine such an aperture after the casting is formed.

Coring the casting is troublesome because of

the difficulty in maintaining uniformity in size and smoothness in the aperture, so as to provide the desired fit for the bit. In the case of forged cutter blocks of this type it is necessary to drill or broach, or both drill 60 and broach this aperture in the forged blank.

In the present invention, the block is provided with an elongated groove, opening to one side thereof, and having a clamping device for holding a bit in this groove. The blank for the improved form of block may be forged or cast, and the bit retaining groove may be finished with a minimum amount of machining by means of a milling 70 cutter or the like. I also provide an improved form of clamp for holding the cutter bit in place, and means for protecting the parts of the clamp from abrasion during the cutting operation.

Referring now to the details shown in the drawings, the cutter chain comprises a series of blocks 10, suitably provided with holes 11^a, 11^b, in which links 11, 11 are connected in the usual manner. The cutter blocks are 80 each provided with a base having a pair of laterally projecting restraining lips 12, 12 which run in oppositely disposed grooves 13^a, 13^b formed in the cutter head 13, as shown in Figure 3. Each block is provided 85 with a cutter bit 16, and the bits are arranged at various angles respective to the cutter head 13. In Figure 3, seven such angles or positions of the cutter bits are shown. The portions of the cutter blocks 90 which extend beyond the cutter head 13 are also arranged at various angles to correspond with their respective cutter bits 16. The general construction of the cutter blocks 95 are the same, however, so that a description of one applies to all.

The body 15 of the cutter block 10 is provided with a lateral opening recess or groove 17 extending from the restraining lip 12 and between the holes 11^a, 11^b outwardly along one side to the outer edge or top of the block. This groove 17 is preferably formed with a relatively restricted portion 17^a adjacent the outer end, and a relatively wider and deeper portion 17^b adjacent the inner end thereof, at the base of the block. The restricted portion 17^a of the groove is finished to receive the cutter bit 16 therein by machining along the sides and bottom thereof, as shown in Figures 6 and 7. The larger 110

portion 17^b is preferably of sufficient width and depth to afford a clearance around the bit when it is in place in the machined groove portion 17^a, as shown in Figure 5, 5 so as to permit the bit to be readily removed from the block.

The bit is secured in place by a clamping member 18 having a portion thereof projecting over the open side of the groove 17 and 10 having engagement with the exposed side of the cutter bit 16. The coacting surfaces of the cutter bit 16 and the clamping member 18 are preferably milled as indicated at 15 to provide a firm grip for the cutter bit. The clamping member 18 is integral with a bolt 20 extending through the body 15 of the block and having a nut 21 threaded thereon to engage the opposite side of said block. In order to protect this nut from 20 abrasion a lateral projection 22 is formed on the block forwardly of said nut.

In the form shown this cutter bit 16^a is inclined forwardly of the block, but it will be understood that the novel features of my 25 invention may be applied to blocks having the bit arranged at any desired angle therein.

Although I have shown and described one form in which my invention may be embodied, it will be understood that the construction and arrangement of the parts may 30 vary widely without departing from the spirit and scope of my invention. I do not therefore wish to be understood as limiting 35 myself to the specific construction illustrated herein excepting as specifically limited in the appended claims.

I claim as my invention:

1. In combination with a cutter bit, a 40 chain block comprising a body provided

with a recess opened throughout its length to one side of said body and adapted to receive said bit in lateral engagement therein, a clamping device extending transversely through said body for retaining said bit in 45 said recess, a nut having threaded engagement with said clamping device on the opposite side of said body for adjusting the tension of said clamping device, and a projection on said body forwardly of said nut for 50 protecting the latter from abrasion.

2. In combination with a cutter bit, a chain block comprising an elongated base provided with a laterally projecting lug, and a body portion extending outwardly 55 from said base, said block having a bit receiving recess opening to one side of said base and body, the outer portion of said recess being relatively restricted to receive said bit in lateral bearing engagement, and the inner portion of said recess adjacent said lug being relatively larger to afford clearance about said bit, and a clamping device 60 for securing said bit in said recess.

3. In combination with a cutter bit, a 65 chain block comprising an elongated base and a body portion extending outwardly from said base, said block having a bit receiving recess opening to one side of said base and body, the outer portion of said recess being relatively restricted to receive said 70 bit in lateral bearing engagement, and the inner portion of said recess being relatively larger to afford clearance about said bit, and a clamping device for securing said bit 75 in said recess.

Signed at Chicago, in the county of Cook and State of Illinois, this 13th day of March, 1923.

CHARLES E. DAVIS.
